UNITED STATES PATENT OFFICE.

OLIVER C. HAYWARD, OF NEW YORK, N. Y.

INDICATOR FOR ELEVATORS.

SPECIFICATION forming part of Letters Patent No. 396,159, dated January 15, 1889.

Application filed February 1, 1888. Serial No. 262,629. (No model.)

To all whom it may concern.

Be it known that I, OLIVER C. HAYWARD, of the city, county, and State of New York, have invented a new and useful Improvement 5 in Indicators for Elevators, of which the following is a full, clear, and exact description.

My invention relates to an improvement in elevator-indicators, and has for its object to provide a simple and economical attachment 10 to elevator-shafts, whereby the approach of the elevator either from below or above will be indicated and the fact made known whether the car is upon the ascent or descent, and wherein also the same fact is set forth upon 15 the stoppage of the car at any floor.

The invention consists in the construction and combination of the several parts, as will be hereinafter fully set forth, and pointed out in the claims.

Reference is to be had to the accompanying drawings, forming a part of this specification, in which similar letters of reference indicate corresponding parts in all the figures.

Figure 1 is a partial vertical section of an elevator-shaft having my invention applied. Fig. 2 is a side elevation of a section of the device. Fig. 3 is a perspective detail view; and Fig. 4 is a partial elevation of the car.

It is the prime object of the present invention to provide a simple and inexpensive indicator capable of use in connection with any shaft and car, which will be composed of few parts, and wherein the fact that the elevator is ascending or descending may be noted by 35 prospective passengers approaching the elevator from any direction. To this end, within the shaft, or within a casing auxiliary to the shaft, the several indicators are pivoted, adapted for engagement with the car. In 40 carrying out the invention I have illustrated the devices as pivoted in the elevator-shaft proper.

At a suitable distance above the flooring of each story, preferably in front of the elevator, 45 an aperture, *a*, is made in the wall *A* of the shaft. Through each aperture *a* the vertical member *b* of an angular indicating-block, *B*, is projected outward, the horizontal member *b'* being pivoted within the shaft to any suitable support and provided at the extremity 50 with a friction-roller, *b''*. The said horizontal member at the pivotal point is provided with

a transverse slot, *b³*, for a purpose hereinafter set forth.

At the extremity of the vertical member *b* 55 a horizontal projection, *b⁴*, is attached or cast integral therewith, which, facing from the front of the elevator, has produced thereon the word "Down" or "Up," according to the placement of the block. The same words are also 60 produced upon the sides of the vertical member, in order that when the blocks are in position to indicate the movement of the car the words may be read from either the front or sides. With the exception of the indicator- 65 block upon the upper floor, all are weighted at the lower outer end to keep the vertical member facing downward and in contact with the outer face of the shaft, as illustrated in Figs. 1 and 2. The block upon the top floor 70 has invariably the word "Down" produced thereon, the outer member being held normally in a vertical position, pointing upward, by the weighting of the inner arm or member. The upper block is also simply pivoted, the 75 slot not being needed.

On the floors intervening the upper and lower stories a second angular block, *D*, is employed, fulcrumed upon the same pin with the blocks *B*. The end projection of the outer 80 member *d* of the said second block extends from one side only, in order that normally the said outer member of the block *D* may rest, pointing downward, essentially in contact and parallel with the block *B* and the shaft. 85

The inner member *d* of the blocks *D* is shorter than the equivalent member of the blocks *B*, and is respectively connected to a lever, *E*, pivoted at one end to the inner wall of the shaft below the blocks, which lever is 90 provided at its other end with a friction-roller adapted for engagement with the elevator-car, as illustrated in Fig. 1. The connection between the blocks *D* and the lever *E* is effected through a bar, *H*, slotted at each end, 95 a pin being passed through the slots, respectively, into the inner member of the blocks and outer end of the lever beyond the fulcrum, as illustrated more clearly in Fig. 2. The outer member of the blocks *D* is weighted, 100 and the lever at its outer under surface likewise, sufficiently to retain the latter, when idle, in a downwardly-inclined position.

The elevator-car is provided with a strip,

II', secured to the front or side, projecting a suitable distance above and below the same, which strip is purposed to engage the levers and all the blocks except that upon the lower floor. This block, which is out of alignment with the others, is engaged by a separate and shorter strip, *h'*, secured to the upper portion of the car and extending above the same. The object of this second strip is to release the lower block almost as soon as the elevator-car has started.

In the event the shaft is so narrow that the blocks cannot be introduced without interfering with the door when open, a casing may be constructed outside the shaft and the shaft slotted to receive the inner members of the blocks and the lever. If found desirable, the strips upon the car may be so placed, and likewise the blocks with relation to the strips, that the blocks will cease to indicate immediately upon the elevator starting from any floor, or just after.

In operation, the car being at the lower floor and the inner member of the block B in engagement with the short strip *h'*, the outer member of the block assumes a horizontal position, having the word "Up" produced thereon. Almost immediately upon the elevator leaving the lower floor the block B is released to assume its normal position. In approaching the next story and before reaching the same the upper end of the strip II, coming in contact with the lever E, causes the outer member of the block D to assume a horizontal position, which, having the word "Up" produced thereon, indicates before the stoppage of the car and after the car has stopped the direction in which it is moving or to move. In its further ascent the car comes in contact with the inner arm of the substantially duplicate block B, upon which the word "Down" is produced; but the car in its upward course does not move the intermediate blocks B to an indicating position, as the slot *b*³ therein allows sufficient movement of the inner arm to permit the free passage of the car without

action of the said blocks. When the upper story is reached, the strip II, coming in contact with the upper block B, causes the vertical member to assume a horizontal position 50 indicating "Down." Leaving the upper floor and going down, the car at the intermediate floors, by means of the strip II', is brought in contact with the several blocks B, raising the outer members to a horizontal position 55 indicating "Down." The lever E does not act when the car is passing down, owing to the slots in the connecting-bar II, the said lever being intended to engage the car for action upon its upward course. 60

Having thus fully described my invention, I claim as new and desire to secure by Letters Patent—

1. In an indicator for elevators, the combination, with a vertical shaft, stages or floors 65 adjacent to said shaft, and the car adapted to travel in the latter, of angle-blocks which are pivoted above such stages or floors, one member or arm thereof projecting through the side of the shaft to engage with the car, and the 70 outer member of said block being provided with an indicating-word and weighted to cause it to hang normally vertical parallel to the side of the shaft, as shown and described, to operate as specified. 75

2. In an indicator for elevators, the combination, with the car provided with side projections, of a double series of angle indicating-blocks, one series provided with a friction-roller upon the inner end adapted to engage the car, a lever connected with the inner member of the second series engaging the car and operating the block, and a horizontal projection integral with the outer member of each series of blocks, the said series having produced upon the faces of the respective outer members the words "Down" and "Up," substantially as and for the purpose specified. 85
